UNITED STATES PATENT OFFICE

GUY E. LINN, OF RITTMAN, OHIO, AND WILLIAM H. FINCKEL, JR., OF WASHINGTON,
DISTRICT OF COLUMBIA, ASSIGNEES TO THE OHIO BOXBOARD COMPANY, OF CLEVE-
LAND, OHIO, A CORPORATION OF OHIO

CONTAINER-TAPING MACHINE

Application filed September 18, 1928. Serial No. 306,737.

In the manufacture of containers, particularly of cartons or shipping cases, having sides and end flaps and formed from a single blank of corrugated or the like composite board, it is customary to secure the adjacent or meeting edges of the blank at a point which ultimately forms a corner of the container, by means of a strip of tape, usually a gummed linen tape, which is applied to the adjacent or meeting edges while the blank is folded flat.

This tape is applied, according to the usual practice, by an automatic taping machine, which feeds the folded blanks, wets the gummed side of the tape, applies the wetted tape, under roller pressure, to the adjacent or meeting edges of the blank, cuts off the tape to the required length to cover the edges throughout their length, and then feeds the taped blanks between conveyor belts which hold the tape to the blank to insure its adhesion thereto, the blanks being finally discharged upon a stacking table or other support.

In those machines of this character with which we are familiar, the intention is to make the travel of the containers between the conveyor belts of such a length that by the time the containers are discharged therefrom the tape will have dried and become firmly united with the adjacent or meeting edges of the blank. In practice, however, it sometimes happens that the tape does not adhere as intended and does not become completely dried by the time the blanks are discharged, with the result that some of the containers are imperfect and have to be either discarded or retaped.

The object of our invention is to provide means whereby this failure in consistent operation of taping machines may be avoided, and loss of time and material incident thereto obviated.

The invention consists in a device adapted for application to taping machines, whereby the tape, while still in a moist condition just subsequent to its application, may be subjected to heat and pressure, or, in effect, to ironing, to insure its proper adhesion to the adjacent or meeting edges of the con-

tainer blank, as we will proceed now to explain and finally claim.

In the accompanying drawings illustrating the invention, in the several figures of which like parts are similarly designated, 55 Figure 1 is a schematic view showing the device of our invention in association with a taping machine of conventional form. Fig. 2 is a front elevation, on a larger scale, of the device of our invention, the bed of the 60 taping machine being shown with containers being taped passing under our device. Fig. 3 is a top plan view, on a larger scale, of our device. Fig. 4 is a section taken substantially on line 4-4 of Fig. 2. Fig. 5 is a 65 perspective view of a folded container or carton blank before the application of the tape, and Fig. 6 is a similar view after application of the tape.

The taping machine proper includes, 70 as essential elements, a bed 1 provided with recesses or a recess in its upper face in which travel a pair of chains or a belt 2 carrying suitably spaced lugs 3 and running over sprockets or rollers 4, one pair 75 of which provides the drive for the chains or belt. Arranged upon the top of the bed 1 is a stop or abutment 5 against which are stacked the folded container blanks *a*, a space or slot being provided in the stop adjacent to the 80 top of the bed 1 through which the blanks *a* may be advanced one-by-one to the taping mechanism by means of the travelling lugs 3. The taping mechanism comprises a suitable support, not shown, on which are mounted 85 a roll 6 of gummed tape *b*, and a plurality of guide rollers 7 which convey and guide the tape into operative relation to a wetting apparatus and a cutting and end applying or sticking apparatus. These latter two 90 apparatus, being of conventional and well-known form, are not illustrated.

In the path of travel of the tape *b* as it is applied to the adjacent or meeting edges *c* of the blanks *a* (see Figs. 1, 5 and 6), we 95 mount the device of our invention. This device comprises a pair of similar ironing and pressure-applying members 8, each of which is fitted with a heating member 9, preferably an electrical resistance element. 100

Each of these resistance elements is provided with terminals 10 and 11 to which positive and negative leads from a source of electric current may be connected. The ironing and pressure-applying members 8 are spaced apart and are connected at their leading ends to an upturned shoe member 12, carrying a block 13, and at their rear ends to a block 14, by means of bolts 15 or other appropriate connections. Each of the blocks 13 and 14 is provided with a screwthreaded rod 16, and these rods extend through and are slidable in holes formed in the ends of a support or bar 17. Springs 18, through which the rods 16 pass, abut at their ends against the blocks 13 and 14, respectively, and against the ends of the bar 17 and exert a downward pressure upon the blocks which tends to force the members 8 into intimate contact with the tapes applied to the container blanks. Obviously, the springs 18 will be relatively stiff so as to provide a requisite pressure or ironing effect upon the tapes in order that the latter may be made to adhere throughout to the adjacent edges of the blanks. Downward movement of the members 8 is limited by means of washers 19 and nuts 20 applied to the rods 16 and adjustable thereon.

It will be understood that the bar 17 is carried by some fixed part of the frame of the taping machine, and it may, if desired, be rigidly applied thereto. But, as it sometimes happens that the machine stops or is stopped with a blank beneath the device of our invention, we consider it advisable to so mount the bar 17 that the ironing and pressure applying members 8 may be raised out of contact with the blanks, so that such blanks, when stopped beneath the members 8, will not be scorched or burned. To this end, we mount the bar 17 for vertical sliding movement, preferably normal to the bed 1, by means of dove-tail tongue and groove connections 21, with a plate 22 supported by a bracket 23 on a portion 24 of the frame of the machine. In order that the bar 17 may be raised and lowered, and held in either of these positions we provide a cam 25 fixed on a shaft 26 having an operating handle 27. This cam 25 bears against a strap 28 carried by the bar 17, and against a seat 29 formed in the bar 17. The shaft 26 is journalled in a vertically adjustable bearing bracket 30 fixed to the frame 24 or to the bracket 23. It will be understood, of course, that means other than the cam arrangement shown may be used in this connection, so long as the operation of raising and lowering the ironing and pressure-applying members and holding them fixed is made possible.

Parallel belts 31 and 32 running over pulleys or rollers 33 and 34, respectively, are employed for conveying the taped blanks, preferably under pressure, from the taping ma-

chine to a stacking table or other point of delivery.

Obviously, the pressure-applying and ironing members 8 will be of such length, and their heating members 9 will maintain such a degree of heat, that when the taped blanks are discharged from beneath them the tapes will have been completely dried and pressed into such intimate contact with the adjacent edges of the blanks as to have adhered throughout their entire blank-contacting areas with such edges. 70 75

By using two of the members 8, instead of a single one of such members of double width, and spacing them apart, as is clearly shown 80 in Fig. 4, we are not only enabled to employ smaller and less expensive resistance elements but we apply the heat and pressure where needed and provide a space through which the vapor produced by the drying of the 85 wetted tape may readily escape.

The operation of the device would seem to be apparent, but, in the interest of clearness, it may be described briefly as follows:—We will assume that the taping machine is supplied with tape and water, and is in condition to function properly, and that the device of the invention is properly adjusted for the thickness of the blank to be operated upon and is heated to the proper temperature by 95 the members 9, and that a supply of folded carton blanks *a* has been stacked against the stop or abutment 5 with the line of their adjacent edges *c* in longitudinal alignment with the tape-applying mechanism and the space 100 between the members 8.

The taping machine being started, the folded blanks *a* will be fed one-by-one by the lugs 3 beneath the taping mechanism where a suitable length of tape will be applied to each and automatically severed from the web of tape coming from the roll of tape 6. The blanks will then pass under the device of our invention, the up-turned shoe 12 facilitating their insertion beneath it. The springs 18, being compressed by the thickness of the blank, will exert pressure upon the tape to cause it to smoothly adhere to the edges *c*, as shown in Fig. 4, the heat supplied by the members 9 at the same time driving off the 110 moisture and ironing the tape, so that when the finished taped blanks emerge from beneath our device, as shown at *e*, (Fig. 1), their joints will be properly, evenly taped and dried 115 and the tape cannot thereafter become loosened or disarranged.

If the taping machine should stop or be stopped when a blank or blanks are beneath our device, the members 8 may be immediately raised out of contact with and removed 125 from injurious proximity to the blank by appropriate manipulation of the cam 25 by means of handle 27, and thus the heat of the members 9 will not burn the tape or the blank.

We have shown and described electrical re- 130

sistance elements as the heating means for the members 8, but it will be understood that steam or hot-water heated elements might be used instead, and various other changes and modifications are deemed to be permissible within the spirit of the invention and the scope of the following claims.

What we claim is:—

1. In a container taping machine, the combination with container feeding and taping mechanisms, of means for applying pressure and heat to the applied tape, said means including a pressure-applying member, a heating member for supplying heat to said pressure-applying member, a support for said members, means interposed between said support and said members for supplying pressure to said pressure-applying member, and manually operable means for bodily adjusting said support to move said members toward and away from the taped containers at the will of an operator.

2. In a container taping machine, the combination with container feeding and taping mechanisms, of means for applying pressure and heat to the applied tape, said means including a pressure-applying member provided with means for supplying heat thereto, a support for said member, resilient means interposed between said member and said support, and means for raising and lowering said support and said member as a unit.

3. In a container taping machine, the combination with container feeding and taping mechanisms, of means for applying pressure and heat to the applied tape, said means including a pressure-applying member provided with means for supplying heat thereto, a support for said member, resilient means interposed between said member and said support, and means including a cam mechanism for raising and lowering said support and said member as a unit.

4. In a container taping machine, the combination with container feeding and taping mechanisms, of means for applying pressure and heat to the applied tape, said means including a pair of spaced pressure-applying members, and a heating member for supplying heat to each of same, the space between said members providing an escape for vapor produced by heating of the tape.

5. In a container taping machine, the combination with container feeding and taping mechanisms, of means for applying pressure and heat to the applied tape, said means including a pair of pressure-applying members, heating members carried thereby, means to which said pressure-applying members are attached adjacent to their ends and by which they are maintained in spaced parallel relation, a support for said pressure-applying members, resilient means interposed between said support and said pressure-applying members and by which pressure is applied thereto

and to said applied tape, and means for vertically adjusting said support and with it said pressure-applying members.

6. In a container taping machine, the combination with container feeding and taping mechanisms, of means for applying pressure and heat to the applied tape, said means including a pair of pressure-applying members, heating elements carried thereby and adapted to supply heat thereto, blocks arranged transversely of said members adjacent to their ends and to which the members are attached in spaced parallel relation, a support, rods carried by said blocks and slidably mounted in said support, and resilient means interposed between said support and said blocks for applying pressure to said members and therethrough to the applied tape.

7. In a container taping machine, the combination with container feeding and taping mechanisms, of means for applying pressure and heat to the applied tape, said means including a pair of pressure-applying members, heating elements carried thereby and adapted to supply heat thereto, blocks arranged transversely of said members adjacent to their ends and to which the members are attached in spaced parallel relation, a support, rods carried by said blocks and slidably mounted in said supports, resilient means interposed between said support and blocks and positioned by said rods, means carried by said rods for limiting movement of said members relatively to said support under the influence of said resilient means, and means for raising and lowering said support and with it said members.

In testimony whereof I have hereunto set my hand this 17th day of September, A. D. 1928.

GUY E. LINN.
